REUBEN J. RANDOLPH, OF MAYWOOD, NEW JERSEY.

DRYING APPARATUS.

Application filed August 12, 1921, Serial No. 491,809. Renewed November 28, 1925.

The present invention relates to improvements in apparatus for drying a continuous strip or web of paper or similar material, and more particularly for drying wall paper or coated paper while the same is in course of manufacture.

The primary object of the invention is to provide novel and improved apparatus whereby the grounding and printing operations employed in the manufacture of wall paper or coated paper with any preparation which necessitates drying may be performed rapidly and continuously and in such manner that the printing operation may quickly succeed the grounding operation and preferably these two operations may be performed during a single passage of the paper strip or web through the apparatus, thus minimizing the amount of handling of the strip or web necessary for the performance of these operations and saving much time, resulting in increased capacity of the apparatus.

One feature of the apparatus consists in providing novel and improved drying means which receives the paper strip or web from the grounding machine and functions to properly dry the same, immediately following which the grounded web is conducted to the printing machine which prints the patterns or figures on the web, the latter passing from the printing machine to drying means which dries the printed pattern and delivers the dried web to a suitable rolling device in condition to be rolled thereon. The drying means are so constructed and operative that the travelling web is quickly, thoroughly and uniformly dried.

Another feature of the invention consists in providing devices for automatically threading the leading end of each paper web from the grounding machine through the drying means to the printing machine and the rolling device, thus avoiding delay and other disadvantages incident to manual threading of each paper web through the apparatus.

Other features of the invention consist in providing open mesh woven or other wire cloth or fabric conveyers for supporting and conducting the paper web through the drying means to accelerate and facilitate drying thereof, the web-supporting sides of the conveyers being supported by idler rolls mounted on anti-friction bearings to insure regular advance of the conveyers with mini-

mum resistance, and hence minimum distortion of the conveyer and the paper web thereon in process of drying, and providing other structural features which will be hereinafter more fully described, the features of novelty being particularly pointed out in the claims at the end of the specification.

In the accompanying drawings:—
Figure 1 represents the grounding and printing end of a wall paper-making machine constructed in accordance with the preferred embodiment of the present invention, the drying means being shown partially in section;

Figure 1^a is a view similar to Figure 1, but showing the rolling end of the machine;

Figure 2 is a side elevation of one end of the drying means;

Figure 2^a shows the opposite end of the drying means illustrated in Figure 2;

Figure 3 is a diagrammatic view in top plan of the end of the drying means shown in Figure 2;

Figure 3^a is a diagrammatic view in top plan of the end of the drying means shown in Figure 2^a;

Figure 4 represents, on an enlarged scale, a transverse section through the drying means with the conveyers and related parts omitted;

Figure 5 represents a transverse section through the drying means showing the conveyers and heating devices, but omitting the enclosing casing; and

Figure 6 is a detail view, on an enlarged scale showing the preferred construction of the conveyer and the anti-friction mounting for one of the idler rolls.

Fig. 7 is a detail view of the driving means for the threader rollers.

Similar parts are designated by the same reference characters in the several views.

The present invention is applicable to all situations or installations where it is desirable or necessary to conduct a strip or web through an apparatus for drying or similar treatments. The invention is particularly applicable, however, to wall paper-making apparatus and the invention is shown in the accompanying drawings as applied to an apparatus of this character and it will be so described hereinafter. It is to be understood, however, that the invention is not restricted to the precise construction shown, as equivalent constructions and analogous applications of the invention are contem-

plated and these will be included within the scope of the claims.

In the present instances, 1 represents generally a grounding machine which may be 5 of the conventional type employed to apply the ground to the paper as the first step in the manufacture of wall paper or coated paper, the strip or web of paper being supplied to the grounding machine from a roll 10 2 which feeds the paper strip or web to a conveyer 3. This conveyer is suitably driven so that its upper side will travel toward the paper-receiving end of the grounding machine, thus assisting in feeding the paper 15 strip or web to the grounding machine in the direction indicated by the arrow, the paper strip or web being designated X.

The paper strip or web, as it discharges from the grounding machine, bears the 20 ground in a wet condition on its upper surface and the paper strip or web is received at this point by a conveyer 4, the ends of which pass over rollers 5 and 6 and the intermediate portions of which may be supported and guided by appropriately-spaced 25 idler rolls 7. Idler rolls 8 are also preferably provided so that the major portion of this conveyer 4 may lie horizontally, while its end adjacent to the grounding machine may be inclined, to bring this end of the conveyer to approximately the same level with the grounding machine and thus facilitate the transfer of the paper strip or web from the grounding machine to the receiving end of this conveyer.

Another conveyer 9 is preferably located above the conveyer 4 and it is adapted to receive the paper strip or web from the conveyer 4 and to impart a reverse movement 40 to the strip or web, thus bringing the paper strip or web to a position to be received by the printing machine, which latter is designated 10 and may be of the conventional form used in the manufacture of wall paper. The conveyer 9 is supported at its 45 ends by rollers 11 and 12 and it may also be supported at intermediate points by appropriately spaced idler rolls 7. Other idler rolls 13 are also provided for this 50 conveyer 9 so that the roller 11 at the delivery end of this conveyer may be located below the level of the remainder of the conveyer, thus bringing the delivery end of the conveyer to approximately the level of 55 the receiving end of the printing machine. Means is provided by the present invention for automatically threading the leading end of the paper strip or web from the lower conveyer 4 to the upper conveyer 9, this 60 threading operation requiring the bending back or doubling of the paper strip or web. Preferably and as shown particularly in Figure 1^a, this threading means comprises a deflector plate 14 which is mounted preferably 65 in relatively fixed position above the roller

6 of the lower conveyer 4, with its lower edge in close proximity to the upper side of conveyer and the threading means also comprises a pair of rollers 15 which are preferably provided on their peripheries with circumferentially spaced axially extending 70 ribs, these rollers being mounted above the upper edge of the deflector plate 14 opposite to the outer side of the roller 12 of the upper conveyer 9, these rollers 15, moreover, being appropriately driven so that they revolve concurrently in the direction indicated by the arrows. When the leading end of a paper strip or web is placed on the upper side of the conveyer 4, the latter travelling 75 toward the right in Figures 1 and 1^a, will carry the web forward in the direction indicated by the solid arrows until the leading end of the strip or web reaches the deflector plate 14. The latter will deflect 80 the leading end of the paper strip or web upwardly toward the passage between the roller 12 and the ribbed rollers 15 and these ribbed rollers will strike the uplifted end of the strip or web and thus cause it to enter the passageway and to bend around the roller 12 of the conveyer 9. As the paper strip or web continues to advance under the influence of the lower conveyer 4, aided by the rollers 12 and 15, the leading 85 end of the strip or web will come to rest on the upper side of the conveyer 9 which is moving in an opposite direction to the direction of movement of the upper side of the lower conveyer 4. The strip or web will 90 thus be advanced by the conveyer 9 until it reaches the delivery end of this conveyer, at which point the paper strip or web having the ground applied thereto will have 95 been dried by the action of the drying means which will be hereinafter described. The strip or web is then delivered to the upper side of the conveyer 16 which moves in a direction to advance the strip or web in the direction indicated by the arrow, thus feeding 100 the grounded paper strip or web into the printing machine 10. The printed strip or web is delivered from the printing machine onto a third or upper conveyer 17 which operates to advance the web toward 105 the opposite end of the machine for rolling when dry. This upper conveyer is mounted at its ends on rollers 18 and 19 and it may be supported at intervals in its length by appropriately-spaced idler rolls 7. Idler rolls 110 20 are preferably provided over which the upper and lower sides of this conveyer pass at an angle, thus enabling the end roller 18 to be located at a sufficiently low level to facilitate transfer of the printed strip or web from the printing machine to this upper conveyer. The printed strip or web is 115 preferably delivered from the printing machine to the upper conveyer by an intermediate conveyer 21 which is mounted on end 120 125 130

rollers 22 and 23 and passes over intermediate rollers 24 which cause the strip or web to be delivered downwardly from the conveyer 21 onto the upper surface of the 5 conveyer 17. The paper strip or web which is caused to travel in the direction of the solid arrows (Figure 1) by the upper conveyer is delivered by suitable rolling means such, for example, as that technically known 10 in the art as a rolling-girl. According to the present invention, a threading device is provided for insuring the correct delivery of the paper strip or web from the upper conveyer to the rolling device. Preferably 15 and as shown, a pair of ribbed rollers 25 are provided for this purpose, they being mounted slightly beyond the delivery end of the upper conveyer 17 in line to receive the leading end of the paper strip or web 20 and these ribbed rollers are driven in the direction indicated by the arrow in Figure 1^a, whereby the leading end of the paper strip or web will be engaged by the rollers 25 and deflected downwardly so that it will 25 engage the upper surface of a conveyer 26 mounted on end rollers 27 and 28. This conveyer 26 will advance the paper strip or web in the direction indicated by the arrow, and the grounded and printed paper strip 30 or web which will have been dried before reaching this point, by the drying means to be hereinafter described, is delivered through the medium of an intermediate conveyer 29 located opposite to the lower or 35 delivery end of the conveyer 26 onto a conveyer 30 which is mounted on end rollers 31 and 32 and serves to advance the dried and completed wall paper to the rolling-girl or other suitable rolling device 33.

40 According to the present invention, means is provided for thoroughly, quickly and uniformly drying the paper strip or web after it leaves the grounding machine and prior to its delivery to the printing machine and 45 also after the paper strip or web has been printed by the printing machine and prior to its delivery to the rolling device. Preferably, the conveyers, 4, 9 and 17 operate in individual drying chambers or ducts and 50 means is provided for supplying heat to the interiors of these chambers or ducts and for creating a flow of heated air therethrough. As shown and as preferred, the conveyers are mounted in superposed relation and the 55 group of conveyers is enclosed by side walls 34 and top and bottom walls 35, these walls being preferably composed of suitable heat insulating material or provided with a suitable heat insulating covering, horizontal 60 partitions 36 forming individual drying chambers or ducts for the conveyers 4, 9 and 17 respectively. Hangers 37 may be suspended from overhead beams of a mill and thus provide supports for the drying 65 apparatus and these hangers may also

be employed advantageously as mountings for the idler rolls 7 of the different conveyers, as is shown in Figure 5. Suitably located steam pipes or coils 38 are preferably provided in the different drying chambers 70 or ducts. In order to facilitate circulation of heated air around the paper strip or web while passing through each drying chamber or duct, each of the conveyers 4, 9 and 17 is preferably composed of an open mesh woven 75 wire or other fabric, as is shown in Figure 5 and illustrated in detail in Figure 6. Also, in order to insure even movement of each conveyer and avoid distortion during its travel, the idler rolls 7 of the different conveyers are preferably mounted on ball bearings 40 or equivalent anti-friction bearings, 80 as shown in detail in Figure 6.

In the preferred embodiment of the invention, air which has preferably been 85 warmed, from a suitable source is forced into the upper drying chamber or duct which contains the conveyer 17, by a blower attached to the air supply inlet 41. The supply air thus introduced into the uppermost drying chamber or duct travels longitudinally thereof and toward the left in Figures 2 and 2^a until it reaches an exhaust conduit 42 which exhaust conduit is preferably provided with an exhaust fan or equivalent means which draws the air from the left-hand end of this drying chamber or duct. To assist the drying action and the circulation of the drying air through the drying 90 chamber or duct, one or more so-called boosters 43 may be provided, if desirable, for forcing air from the atmosphere, or other parts of the drying system, into the drying chamber or duct in the direction in which the air within the drying chamber 95 or duct is moving. Supply air from a suitable source is introduced into the left-hand end of the intermediate drying chamber or duct which contains the conveyer 9, by a blower or equivalent means 44 and this air, 100 upon reaching the right-hand end of such drying chamber or duct is transferred by the conduit 45 to the right-hand end of the lowermost drying chamber or duct which contains the conveyer 4, the air being thus 105 caused to double upon itself and to travel toward the left in the lowermost drying chamber until it reaches the conduit 46 which communicates with the exhaust conduit 42, the air from the lowermost drying 110 chamber being thus drawn from its left-hand end. Boosters 47 and 48 similar to the booster 43 may be provided, if desirable, for these middle and lowermost drying chambers or ducts, to assist the movement of air 115 through these chambers or ducts and to facilitate or promote the drying operation. In order to insure efficient contact between the longitudinally travelling air in the different drying chambers or ducts and the 120

surface of the paper strip or web to be dried, offsets or baffles 49 may be arranged, if desirable, on the roofs of the drying chambers or ducts and positioned to deflect the longitudinally travelling bodies of air downwardly so as to contact at close intervals with the surface of the paper strip or web. It will be understood that if desirable the air passing through the chamber containing the conveyer 9 may be discharged to the atmosphere or elsewhere instead of being discharged into the compartment of the conveyer 4 and other air used in the compartment of conveyer 4, or that the direction of circulation may be reversed in any or all compartments and that any proportion of return air or fresh air may be used throughout any one of the compartments. It will also be understood that the walls of the drying chambers or ducts may be provided with doors or movable panels to permit ready access to the interiors of the drying chambers, and inspection openings 50 covered by glass or other transparent medium may be provided at suitable intervals in the lengths of the drying chambers or ducts to enable inspection of the web during its travel through the drying means.

Fig. 7 illustrates one mode of driving the threadder rollers 15, 15 and 25, 25. In this instance, the roller 19 of the conveyer 17 is provided with a belt pulley 50 with which a crossed belt 51 cooperates, this belt driving a pulley 52 in a direction the reverse of that in which the roller 19 revolves. Other belts 53 and 54 serve to drive the threadder rollers 25, 25 concurrently in the direction indicated by the arrows. The threadder rollers 15, 15 are preferably similarly driven from the roller 42 of the conveyer 9 and in the direction indicated by the arrows. Any suitable or well known means may be provided for driving the conveyers 4, 9 and 17 and the auxiliary conveyers 16, 21, 26 and 29 in the proper directions and at the proper relative speed and for driving the grounding machine 1, printing machine 10 and the rolling device 30 in proper timed relation with the conveyers, and hence illustration of any particular driving means for this purpose is thought unnecessary.

The apparatus hereinbefore described comprises one complete unit of the machine and it is to be understood that any desired number of these units may be used to make up a machine, it being only necessary to duplicate the unit heretofore described, the units being preferably arranged side-by-side, and exhaust conduit 42 may be used as a common exhaust for the outlets of the uppermost drying chambers or ducts and also the auxiliary exhaust conduits 46 which lead from the outlets of the lowermost drying chambers or ducts. Likewise, the blowers 41 and 44 may be connected in common to sup-

ply the drying air to the respective drying chambers or ducts of the different units.

The present invention provides apparatus capable of rapidly, thoroughly and uniformly drying a strip or web of paper or other material and it is particularly applicable to the manufacture of wall paper or coated paper, it enabling the printing operation in the manufacture of wall paper, to be performed promptly after the grounding operation and by a single continuous passage of the paper strip or web through the machine, and moreover, the finished paper will be ready for rolling, reeling or cutting up promptly after the performance of the printing operation or the coating operation. By supporting the wet grounded or printed paper strip or web on an open mesh woven wire or other open mesh fabric while subjecting the same to the action of the drying air, the circulation of the drying air over and around the paper strip is facilitated and hence the drying action is greatly promoted.

By providing automatic threading means for properly conducting the leading end of a paper strip or web through the different elements of the machine, manual handling of the strip or web is reduced to a minimum thus effecting a substantial saving in time, labor and waste material.

I claim as my invention:—

1. In apparatus of the character described, the combination with a pair of superposed conveyers operative to advance a strip or web in reverse directions, of means for removing the strip or web from one of the conveyers at a point near its delivery end, and means for reversing the direction of movement of the strip thus directing it onto the receiving end of the other conveyer.

2. In apparatus of the character described, the combination with a pair of superposed conveyers operative to advance a strip or web successively in opposite directions, of means for lifting the strip or web from the lower conveyer as said strip approaches the delivery end of such conveyer, and means arranged to receive the lifted strip and operative to deflect the same onto the upper surface of the upper conveyer.

3. In apparatus of the character described, the combination with a pair of superposed endless conveyers having supporting rollers at their ends, of means for removing a strip or web from one of said conveyers as it approaches the delivery end thereof, and means including a roller located opposite to the supporting roller at the receiving end of the other conveyer and rotatable in a direction to convey the strip or web between it and said other conveyer.

4. In apparatus of the character described, the combination with a pair of superposed reversely-moving endless conveyers having supporting rollers at their ends, of means

operative to remove a strip or web from one of the conveyers as the strip approaches the delivery end of such conveyer, and a pair of ribbed rollers located opposite to the supporting roller at the receiving end of the other conveyer and operative to engage and conduct the strip onto said other conveyer.

5. In apparatus of the character described, the combination with an endless conveyer, 10 and a receiving conveyer located below its delivery end, said conveyers being movable in reverse directions, of a device located adjacent to the delivery end of the first-mentioned conveyer and operative to reverse 15 the direction of movement of a strip or web advanced thereby and to direct such strip onto the receiving conveyer.

6. In apparatus of the character described, the combination with an endless conveyer 20 having a supporting roller at its delivery end, and a receiving conveyer located below the delivery end of the first-mentioned conveyer, said conveyers being operative to advance a strip or web in opposite directions, 25 of a ribbed roller mounted opposite to the supporting roller at the delivery end of the first-mentioned conveyer and rotatable in a direction to bend and deflect a strip or web advanced by such conveyer onto the receiving 30 conveyer.

7. In drying apparatus of the character described, in combination, a relatively long narrow closed drying duct, means for advancing the medium to be dried longitudinally therethrough, means for forcing drying air into one end of the duct, means for withdrawing air from the opposite end of the duct, and means located intermediately of the length of the duct for boosting the 40 flow of air therethrough.

8. In drying apparatus of the character described, in combination, a relatively long, narrow closed duct, an open mesh conveyer for supporting and advancing a strip or 45 web therethrough, heating means located inside the duct, and means for inducing a flow of drying air longitudinally through the duct at both the upper and lower sides of a strip or web on said conveyer.

50 9. In drying apparatus of the character described, in combination, a relatively long narrow duct, an open mesh flexible conveyer for supporting and advancing a wet paper web longitudinally through the duct, 55 idler rolls with anti-friction bearings supporting said conveyer at intervals in its length, heating means located inside the duct, and means for inducing the flow of a current of drying air longitudinally through the duct and in paths above and below the web on the conveyer.

60 10. In drying apparatus of the character described, in combination, a relatively long narrow duct having closed longitudinal walls, means for advancing a web longitu-

dinally through the duct, means for inducing the flow of a current of drying medium longitudinally through the duct, and means for deflecting the longitudinally moving current of drying medium at longitudinal 70 intervals into contact with the surface of the web.

11. In web drying apparatus, the combination of a relatively long narrow duct having closed longitudinal walls, means for advancing a web longitudinally therethrough, means for inducing the flow of a current of a drying medium longitudinally through the duct, and deflectors arranged at intervals 75 along a longitudinal wall of the duct opposite to one of the surfaces of the web and operative to divert such current into contact with said surface of the web.

12. In a drying apparatus of the character described, the combination of a plurality of relatively long narrow individual drying ducts arranged in superposed relation, conveyers in the respective ducts for advancing a strip successively through the different ducts, an air-transfer conduit connecting an end of one of said ducts to the adjacent end of another of said ducts, and means for inducing the flow of a current of air individually through each duct. 80

13. In drying apparatus of the character described, the combination of a plurality of relatively long narrow drying ducts arranged in superposed relation, conveyers for advancing a web in different directions and successively through the ducts, means for supplying air to said ducts and means for withdrawing air from said ducts and for inducing the flow of a current of air longitudinally and individually through each 85 duct in a direction opposite to the direction 90 of movement of the web therein.

14. In drying apparatus of the character described, the combination of a plurality of relatively long narrow drying ducts arranged in superposed relation, conveyers for advancing a web in different directions and successively through the ducts, means for supplying air to said ducts and means for inducing the flow of a current of air individually and longitudinally through each 100 duct in a direction parallel to the direction 105 of movement of the web therein.

15. In drying apparatus of the character described, the combination of a plurality of relatively long narrow drying ducts arranged in superposed relation, conveyers for advancing a web successively in different directions through the ducts, means for inducing a flow of a current of drying air 110 through each duct, the drying air being transferred from one end of one of the ducts to the adjacent end of another duct, and means for drawing air from said ducts. 115

16. In a wall-paper making machine, 120 the combination of a grounding machine, 125

drying means arranged to receive a wet grounded paper strip from the grounding machine and operative to dry such strip, and a printing machine arranged to receive and 5 to operate on the dried grounded strip from the drying means.

17. In a wall-paper making machine, the combination of a grounding machine, drying means arranged to receive a grounded 10 paper strip from the grounding machine, a

printing machine arranged to receive and operate on the grounded strip delivered from said drying means, other drying means arranged to receive the grounded and printed strip from the printing machine, and rolling means arranged to receive the strip from the latter drying means. 15

In testimony whereof I have hereunto set my hand.

REUBEN J. RANDOLPH.
